UNITED STATES PATENT OFFICE

PETER D. B. PAVONE, OF BRIDGEPORT, CONNECTICUT

SAND SCREEN

Application filed May 24, 1926. Serial No. 111,217.

This invention relates to a machine for screening sand or the like, and has for an object to provide an improved construction and arrangement of the screening device which will be simple in construction, which will have a greater capacity for the size of screens used, and will be very efficient and effective in operation.

It is also an object of the invention to provide a screen of a relatively large capacity which will occupy comparatively small space.

With the foregoing and other objects in view, I have devised the construction illustrated in the accompanying drawing forming a part of this specification, similar reference characters being employed throughout the various figures to indicate corresponding elements. In this drawing,

Fig. 1 is a side elevation of the device.

Fig. 2 is a vertical transverse section substantially on line 2—2 of Fig. 1, and

Fig. 3 is a top plan view of the left hand end of the machine as viewed in Fig. 1.

The machine as illustrated comprises a frame having base members 10 at the sides thereof and upright members 11 mounted on the base members. In the form shown there are four of these uprights arranged in a rectangle, and the uprights are connected by longitudinally extending side members 12 and 13 and they are also connected by cross beams 14. In this frame is mounted a pair of screens 15 and 16 in superposed relation. The upper screen 15 is preferably of a larger mesh than the lower screen to first give a rough screening of the material and remove the larger particles and to insure a uniform material being fed to the lower screen. The screens themselves may be of any suitable material, such as woven wire mesh. At their lateral side edges are upwardly extending side members 17 and at one end is a similar cross member 18. The screens are preferably somewhat inclined, as shown in Fig. 1, and there is no upright cross member at the lower end so that the material which is too large to pass through the screen may be discharged at this lower end. Extending transversely of the frame below the discharge ends are inclined

chutes 19 and 20 to carry the material to one side.

The screens are mounted in a novel and effective manner to permit reciprocating movement thereof without sliding connections, and therefore, with a minimum of friction. The upper screen is carried by upright links 21, there being four of these links, two on each side thereof. Of course, the number may be increased if found desirable. These links are pivoted at their upper ends to the screen, as shown at 22, and at their lower ends to the lower side member 14 of the frame, as shown at 23. The lower screen is mounted on similar upright links 24 which are pivoted at their upper ends to the upper side member 13 of the frame, as indicated at 25, and at their lower ends they are pivoted to the screen, as indicated at 26. It will be apparent that the screens may be reciprocated back and fourth on these links as supports. It is preferred that they move in opposite directions, that is, that one screen be moved to the right while the other screen is moving to the left. A simple and effective means for doing this is an upright lever 27 pivoted to the frame at 28 and pivotally connected to the two screens at 29 above and below this pivot, the pivot 28 being on the central side member 12 of the frame. The lever is extended below the lower screen and is connected by a link 30 with a crank 31 on a shaft 32. It is preferred to provide this lever and crank on both sides of the frame so as to give uniform operation of the screen from both sides. The shaft is operated by any suitable device, such as a motor 33 having suitable driving connection therewith, such as a belt 34.

Below the lower screen is a conveyor 35 for conveying the screened material from under the screen where it is easily accessible. This may be of any suitable type but is preferably a simple belt conveyor passing over two drums 36, one of which is on the shaft 32 and operated thereby, and this conveyor discharges screened material at the rear end of the machine. To also prevent shaking or discharging of the material being screened over the sides of the screens, or that is, spill-

ing of the same, upwardly and outwardly inclined guides 37 are provided about the upper edge of the screens. I also preferably provide downwardly and inwardly inclined guides 38 on the under sides of these screens and stationary guides 39 may be carried by the frame over the conveyor 35. Although a feed hopper is not necessary I prefer to provide one as it gives a more uniform feed of the material. Such a hopper is shown at 40 and has a lower open end discharging onto the upper screen.

It will be apparent from the foregoing description that the lever 27 will be rocked about its pivot by the crank 31 through the link 30 as the shaft 32 is rotated. As the lever is connected on opposite sides of its pivot to the two screens these screens will be reciprocated in opposite directions and the specific mounting of these screens on the upright links 21 and 24 permits this reciprocating movement with a minimum of friction. There is usually enough play or looseness in the connections so that a more or less of a jerk or a quick change of direction is imparted to the screens to give a shaking effect to increase the flow of material through the screens. The operation is continuous because the material too large to pass through the screens is discharged at the lower or discharge ends of the screens into the side chutes 19 and 20, and the screened material is discharged at the right hand or rear end of the conveyor 35. It has been found in practice that this screening device is very effective, requires comparatively little power to operate and has a large capacity.

Having thus set forth the nature of my invention, what I claim is:

40 A screening device for sand and similar material comprising a frame, a pair of longitudinally inclined screens arranged one above the other and each comprising a foraminous member and upright side members with one end member about the foraminous member, the other end providing a free exit for material too large to pass through the screens, laterally extending chutes under said free exit ends for carrying away the material received therefrom, a pair of rigid upright links pivoted at their upper ends to the upper screen adjacent each end thereof and pivoted at their lower ends to the frame, a pair of similar rigid upright links pivoted at their lower ends adjacent each end of the lower screen and pivoted at their upper ends to the frame, an upright lever pivoted intermediate its ends to the frame and having pivotal connection with the respective screens on opposite sides of said pivot whereby oscillation of said lever will simultaneously shift the screens longitudinally in opposite directions on their supporting links, downwardly and inwardly inclined deflector plates secured to each screen and extending longitudinally thereof

at their under lateral sides, longitudinally extending upwardly and outwardly inclined deflector plates at the upper lateral sides of the screens with these latter plates on the lower screen extending outwardly of the lower deflector plates on the upper screen, a conveyor under the lower screen to convey the screened material therefrom out of the frame at the opposite end of the frame from the laterally extending chutes, a shaft, means for driving the shaft, a crank operated by the shaft connected to said lever, and means for operating the conveyor from said shaft.

In testimony whereof I affix my signature.
